UNITED STATES PATENT OFFICE.

FRANK S. INGOLDSBY AND JOSEPH R. BOWLING, OF ST. LOUIS, MISSOURI,
ASSIGNORS TO THE INGOLDSBY AUTOMATIC CAR COMPANY, OF ST.
LOUIS, MISSOURI, A CORPORATION OF WEST VIRGINIA.

BOLSTER.

SPECIFICATION forming part of Letters Patent No. 749,293, dated January 12, 1904.

Original application filed February 2, 1903, Serial No. 141,415. Divided and this application filed May 9, 1903. Serial No. 156,358.
(No model.)

To all whom it may concern:

Be it known that we, FRANK S. INGOLDSBY and JOSEPH R. BOWLING, both citizens of the United States, residing at St. Louis, in the 5 State of Missouri, have invented a certain new and useful Improvement in Bolsters, of which the following is a full, clear, and exact description, reference being had to the accompanying drawings.

10 The invention relates to certain improvements in bolsters for railroad-cars, being designed more especially with reference to dumping-cars of the "Ingoldsby" type.

The features which are peculiar to the present invention will be herein clearly described, and definitely set out in the claims, to which reference is hereby made for a summary of the invention.

15 In the drawings, Figure 1 is a side elevation of the bolster. Fig. 2 is a plan view thereof. Figs. 3 and 4 are cross-sections thereof on the correspondingly-numbered lines of Fig. 1.

The bolster J includes the lower compression member in the form of a channel-beam 20 *j*, a center frame *j'*, and a tension-strap *j''*, the tension and compression members passing over the ends of the center frame and having their own ends secured together. The ridge-plate F, which is of the pattern usually employed in the Ingoldsby car, may pass through

25 the bolster between the center frame and the tension-plate and be there secured by bolts *j*³, as shown and claimed in our application, Serial No. 120,922, filed August 25, 1902.

30 At its outer ends the tension-strap *j''* may be turned downward across the end of the compression member and be surmounted by a stirrup *j*⁴, lying over the tension member and riveted to the sides of the compression member, as shown and claimed in application, Serial No. 121,155, by Messrs. Bow-

35 ling and Lombard, filed August 27, 1902. The peculiar feature of the present bolster, however, is the additional tension-strap *j*⁵, 40 which is the full width and length of the bolster and passes between the center frame and

the compression member and then diagonally upward over the struts *j*⁶ and then downward along the tension-strap *j''* and over the end of the compression member. The ends of the 50 tension members *j*² and *j*⁵ are riveted to an angle-clip *j*⁷, secured to the channel-beam *j*. These two tension-straps *j*² *j*⁵, the stirrup *j*⁴, the compression member *j*, and a filler-block *j*⁸ are all riveted together by vertical rivets 55 *j*⁹. Beneath the center casting *j'* and below the compression member is the usual center bearing *j*¹¹, while within this channel member and substantially beneath the struts *j*⁶ are the side bearings *j*¹². When the load in the 60 car is evenly supported, the stress passes to the center bearing *j*¹¹ by means of tension in the strap *j''* and compression in the channel member *j* and the center casting *j'*. When, however, the car-body tips by reason of centrifugal force or unequal loading, so that one side bears down on either side bearing, this 65 makes an upward stress along the strut *j*⁶, which stress is taken care of by the tension-strap *j*⁵. This tension-strap *j*⁵ and the strut 70 *j*⁶ and the compression member *j* thus constitute a local truss taking care of the upward stress when the side bearings engage. This is the peculiar feature of this bolster and one of the important features of the present 75 invention.

The main struts *a'* of the car side, the plates *a*³ of the side girders, and the channel-beams *a*⁹, which form extensions of the lower chord of the car sides, rest on and are secured to the 80 stirrup-plates *j*⁴ of the bolster. These details of the car side form no part of the invention covered by this application, the same being embodied in our application, Serial No. 141,415, 85 filed February 2, 1903, of which this is a division. The diagonal I-beams *N*, passing through the car from its ends to its sides, pass through the bolster and are secured by connecting-plates *n* to the struts *j*⁶.

Having described our invention, what we 90 claim, and desire to secure by Letters Patent, is—

1. In a bolster, a center frame, tension and compression members secured thereto and connected together at their ends, a strut intermediate of said members and an additional tension member extending between the center frame and compression member and between the strut and tension member and connected at its end with the common end of the tension and compression members.
2. In a bolster, the combination of tension and compression members, and intermediate strut members, of an additional tension-strap passing beneath one strut and over another and serving as a local truss to take the upward stress at the side bearing, said extra tension-strap being of the full width and length of the bolster and continuing near its ends alongside of the main tension-strap.
3. In a bolster, the combination of a center

frame, a compression member and a tension member, said members extending across the center frame and having their ends connected together, intermediate struts between said members, and an extra tension-strap extending from end to end of the bolster and passing between the center frame and the compression member and then between the tension members and the intermediate struts, and then following along the inner side of the tension member to the ends of bolster.

In testimony whereof we hereunto affix our signatures in the presence of two witnesses.

FRANK S. INGOLDSBY.
JOSEPH R. BOWLING.
